HEDGE TRIMMER

William E. Bartasevich, Jr., Glenshaw, and James E. Edgell, Bradford Woods, Pa., assignors to Disston, Inc., Pittsburgh, Pa.

Filed Mar. 4, 1971, Ser. No. 121,237

Term of patent 14 years

Int. Cl. D8—03

U.S. Cl. D8—8

FIG. 1

FIG. 2

FIG. 3

FIG. 4

FIG. 5

FIG. 1 is a side elevation of a hedge trimmer showing our new design. The broken lines representing the fragmentary blade element are shown for illustrative purposes only;

FIG. 2 is a plan view;

FIG. 3 is a bottom view;

FIG. 4 is a front end view;

FIG. 5 is a rear end view.

We claim:

The ornamental design for a hedge trimmer, substantially as shown and described.
